UNITED STATES PATENT OFFICE.

HENRY C. FOSBERG AND DOUGLAS H. STRACHAN, OF JAMESTOWN, NEW YORK, ASSIGN-
OES TO ART METAL CONSTRUCTION COMPANY, OF JAMESTOWN, NEW YORK, A COR-
PORATION OF MASSACHUSETTS.

FILING DEVICE.

1,266,444.

Specification of Letters Patent. Patented May 14, 1918.

Application filed April 24, 1917. Serial No. 164,156.

To all whom it may concern:

Be it known that I, HENRY C. FOSBERG, a citizen of the United States, and I, DOUGLAS H. STRACHAN, a subject of Great Britain, having declared my intention of becoming a United States citizen, residing at Jamestown, in the county of Chautauqua and State of New York, have invented new and useful Improvements in Filing Devices, of

10 which the following is a specification.

This invention relates to filing devices and is particularly designed for containing cards or loose leaves. It is an important object of the invention to enable the convenient adjustment of the device so that the contents thereof may be conveniently accessible and readable without removing individual cards or sheets therefrom.

It is a further object of the invention to 20 provide for the convenient moving of selected cards into adjusted positions whereby they may be partially separated from the remaining cards in order that convenient access may be had thereto without going through the entire set of cards.

With these and other objects in view, the present invention consists in the combination and arrangement of parts, as will be hereinafter more fully described, shown in the 30 drawings, and particularly set forth in the appended claims, it being understood that changes in the form, proportion, size and minor details may be made, within the scope of the claims, without departing from the 35 spirit or sacrificing any of the advantages of the invention.

In the drawings,

Figure 1 is a perspective view of a filing device embodying the features of the present invention.

Fig. 2 is a central longitudinal view on an enlarged scale.

Fig. 3 is a cross-sectional view on the line 3-3 of Fig. 2.

45 Fig. 4 is an enlarged fragmentary detail sectional view showing the hinge connection between the base and the bottom of the device.

Fig. 5 is an enlarged detail fragmentary 50 sectional view showing the manner of securing the adjustable card guides.

Fig. 6 is an enlarged detail fragmentary sectional view showing the manner of mounting one of the adjustable card stops.

Fig. 7 is a detail view on a small scale of 55 the type of card for which the present filing device is particularly designed.

Fig. 8 is a fragmentary elevation of the propping means for the hinged bottom.

Like characters of reference designate cor- 60 responding parts in all the figures of the drawings.

The present embodiment of this invention, as shown in the accompanying drawings, includes as its main parts a rectangular base 65 A, an adjustable bottom B, a fixed or stationary back C and an adjustable follower D. It will, therefore, be seen that the device is in the nature of a tray, the bottom B normally resting flat on the base A. The cards 70 or loose sheets rest on the bottom and are held tightly between the back C and the adjustable follower D.

Each of the four sides of the base is a 75 channel bar, as will be seen by reference to the various sectional views. At each corner, the base is supported upon a foot, preferably in the form of a rubber button 1 having a shank 2 extending upwardly through a suitable opening in the lower flange member of 80 the base. The purpose of these feet is to permit of the tray being used upon the top of a desk, table or the like, without scratching the same. Suitable bail or loop-shaped handles 3 are provided at each end of the 85 base for convenience in carrying the device from place to place.

The bottom of the tray B is divided transversely into substantially duplicate front and back sections, the meeting edges of 90 which are hinged together as at 4 by a hinged connection or joint which may be broken upwardly, as indicated in Figs. 1 and 2 of the drawings. Each bottom member or section consists of a flat metal plate having 95 each side edge bent downwardly and thence across the lower side of the bottom so as to form a bead or channel 5, best illustrated in Fig. 6 of the drawings. This channeled or beaded edge gives strength and stiffness to 100 the bottom section, and also has another function, as will hereinafter appear. The outer end of the front bottom section is provided with a finishing strip 7 in the form of an angle bar which has its horizontal member 105 extending across the top of the bottom plate and its vertical member extending downwardly therefrom and terminating sub-

stantially in the plane of the bottom of the channels or beads 5 along the side edges of the plate. A similar finishing strip 7 is provided along the outer edge of the rear bottom plate, as best shown in Fig. 4 of the drawings. The meeting ends of the beaded edges of the bottom plates are beveled or shaped as at 8 so as to permit of the upward breaking of the joint 4 which connects the bottom sections. The outer or rear end of the rear section of the bottom is hinged, as at 4' to the top of the rear end of the base, so as to permit of the bottom sections assuming the position shown in full lines in Fig. 1 and in dotted lines in Fig. 2.

In order that the bottom sections or members may be held in the adjusted positions, shown in Figs. 1 and 2, suitable propping means is provided, such for instance as a plurality of abutments, preferably in the form of pins or projections 9, extending outwardly from the sides of the base at the forward end thereof, the front bottom section being provided at each side with a lug or foot 10 having a notch or seat 11 in its front edge to engage one of the pins or projections 9 and thereby hold the bottom in one or more adjusted positions.

For the support of cards, loose sheets or the like, the rear bottom section is provided with the upstanding back C, preferably in the form of a metal plate having flanged upright edges 12. This back is secured rigidly in some suitable manner to the top of the bottom section, and is also provided at its upper edge with a bifurcation 13 to facilitate access to cards or sheets which are of less height than said back.

On the front bottom section is a follower D, preferably in the form of a metal plate, having a bifurcation 14 in the upper end thereof. This follower is capable of adjustable movement toward and from the back C so as to clamp papers or cards against the back, in the usual manner.

For the mounting of this follower, each bottom section or member is provided with a substantially rectangular depression 15 extending from front to rear of the section, and in this depression there is a channel-bar 16 having inwardly directed flanges 17 extending from the sides of the channel and spaced from and overhanging the back or bottom of the channel. This channel is held fixed in place by suitable fastenings, such for instance, as rivets 18 extending through the bottom of the depression 15. The two channels 16, one in the front bottom section and one in the rear bottom section, are open at their adjacent ends and come into longitudinal alinement in the normal flat condition of the bottom so that the follower may be moved readily across the joint between the two sections. On the bottom of the follower there is provided a foot or

slide 19 which works in the guideway formed by the channel 16, and mounted on the front or outer side of the follower D is a suitable pivoted spring-pressed dog 20 disposed so that its bottom edge may frictionally engage the flanges 17 of the channel or guideway 16 and thereby hold the follower fixed in any adjusted position. 70

At each side of and substantially parallel with the guideway 16, there is a guide 21 extending from front to rear of each bottom section or member. This guide is for the purpose of guiding notched cards, as will hereinafter appear. The bottom edge of the follower D is provided at each side of the guideway 16 with a notch 22 to accommodate the guide 21. Outside of the guide 21, the follower is provided with a foot 23 to slidably bear upon the bottom and hold the follower in an upright position. As best 75 indicated in Fig. 3 of the drawings, it will be seen that each guide 21 is in the form of an inverted substantially U-shaped channel having its lower edges resting upon the bottom plate B. For the purpose of securing 80 each guide to the bottom plate, said guide is provided adjacent each end with a threaded pin or stud 24, best shown in Fig. 5, and this stud or pin extends downwardly through a slot 25 extending transversely 85 through the bottom plate. A winged or other nut 26 is provided upon the lower end of the threaded pin which projects beneath the bottom plate, so that by tightening the nut against the underside of the bottom 90 plate, the pin 24 and the guide 21 may be readily held in place at any adjustment 95 within the limits of the slot 25. While the studs or pins 24 may be independent of one another, it is preferred to employ a rod 27 100 housed within the guide 21 and spot-welded or otherwise rigidly secured thereto, each end of the rod being bent at substantially right angles thereto and screw-threaded, so as to form the screw-threaded pin or stud 24. 105 It will, of course, be understood that the corresponding guides 21 on the front and rear bottom sections or members must be disposed in longitudinal alinement in order 110 that there may be a continuous guide from front to back of the device. 115

Each bottom member is provided at one or both sides, as may be desired, with card stops, each stop consisting of a rod or bar 28 disposed horizontally above the bottom member and provided at opposite ends with depending arms 29 which are provided at their lower ends with inwardly-directed portions 30, each of which passes through an opening 31 in the beaded edge 5 of the bottom member and also through a block 32 rigidly secured within the bead 5 by spot-welding or otherwise. A set-screw 34 pierces the bottom of the channel or bead 5, so that it may be set up tightly against the part 30 to 120 125 130

hold the stop bar or bracket in any adjusted position within the limits of the parts 30.

The present device is primarily designed for containing cards or loose leaves of the 5 type shown in Fig. 7, wherein the reference character 35 designates a card or sheet provided at its lower edge with a plurality of notches 36.

In using the device, the guides 21 are adjusted laterally so as to come into alignment 10 with the corresponding notches 36 in a plurality of cards 35, such cards, of course, containing data which has been entered thereon. One of such cards has been indicated in dotted lines at E in Fig. 3 of the drawings, 15 wherein it will be seen how certain of the notches of the card engage the guides 21 so as to hold the cards against edgewise displacement and also to guide them when they 20 are moved longitudinally of the device. When the follower D is set up against a plurality of such cards, the latter are clamped tightly between the back C and the follower D.

25 Whenever it is desired to have access to any of the cards, the joint 4 of the bottom is broken upwardly and each of the feet 10 is engaged with one of the shoulders or projections 9 so as to support the bottom in a 30 position such as shown in Fig. 1 and in dotted lines in Fig. 2 of the drawings. Before bringing the bottom into this adjusted position, the follower D is of course backed away from the cards to a suitable position 35 upon the front bottom section or member. When the bottom of the tray has thus been adjusted, the cards on the rear bottom section will be tilted backwardly at an angle for convenient inspection. After inspection 40 the cards may be moved forwardly and placed against the rear side of the follower D. If it becomes necessary to subsequently refer to cards already referred to, such cards may be drawn edgewise out of alignment 45 with the rest of the cards until others of the notches 36 engage the guides 21, as shown in dot and dash lines at F in Fig. 3. In order that a card may be quickly placed in this position, the stop brackets 28, at one 50 side of the device, are first adjusted to such a position that when a card is brought up edgewise against the bracket, certain of the notches of the card will be in alignment with the guides 21. After going through 55 all of the cards, it is a very simple and convenient thing to refer back to the selected cards, because such selected cards project laterally from the series of cards. When reference to the cards has been completed, 60 the tray bottom is returned to its horizontal position upon the base, and the follower moved forwardly so as to clamp the cards between the stationary back and the follower. The cards which have been pulled 65 out against the stops 28 can be returned to

their normal positions or they can remain in their adjusted positions without interfering with the clamping of the cards between the stationary back and the follower.

Having thus described the invention, what 70 we claim is:

1. A filing device comprising a bottom divided into a pair of sections having a hinge joint capable of breaking upwardly, an upright rising from each bottom section 75 to support the contents of the filing device in normal and adjusted positions of said bottom, and propping means carried by the outer free end portion of one of the bottom sections for engagement with the support 80 on which the filing device rests.

2. A filing device comprising a bottom divided into a pair of sections having a hinge joint capable of breaking upwardly, an upright rising from each bottom section 85 to support the contents of the filing device, and propping means carried by one of the bottom sections.

3. A filing device comprising a bottom divided into a pair of sections having a 90 hinge joint capable of breaking upwardly, an upright rising from each bottom section to support the contents of the filing device, a hinged support for one end of the bottom 95 and propping means carried by the bottom for engagement with the support on which the filing device rests for maintaining the bottom sections with the hinge joint broken upwardly.

4. A filing device comprising a base, a 100 bottom hinged at one end to the base and divided into a pair of sections having a hinge joint capable of breaking upwardly to an adjustable position, and cooperating means between one of the sections and the 105 base for maintaining the bottom in an adjusted position with the hinge joint broken upwardly.

5. A filing device comprising a base, a 110 bottom hinged at one end to the base and divided into a pair of sections having a hinge joint capable of breaking upwardly to an adjusted position, a plurality of stop members on the base, and a device on one of the bottom sections for selective engagement 115 with the stops to prop the bottom in an adjusted position.

6. A filing device comprising a base, a 120 bottom hinged at one end thereto and divided into a pair of sections having a hinge joint capable of breaking upwardly, a series of shoulders projecting laterally outward from opposite sides of the base, and members on one of the bottom sections for selective engagement with the shoulders to prop 125 the bottom in an adjusted position.

7. A filing device comprising a bottom divided into a pair of sections having a hinged joint capable of breaking upwardly, a back rising from one of said bottom sec- 130

- 4 1. A filing device comprising a bottom, a back rising therefrom, a follower having a slide mounted on the 5 guideway, a hinge joint capable of breaking upwardly, a back rising from one of the bottom sections, and a follower carried by the bottom and movable toward and away from the back, and card guides on each bottom section, corresponding card guides of the two bottom sections being in endwise alinement in the 10 normal position of the bottom sections.
2. A filing device comprising a bottom divided into a pair of sections having a hinge joint capable of breaking upwardly, a back rising from one of the sections, a 15 guideway leading toward the back, a follower mounted upon the guideway, and card guides at opposite sides of and substantially parallel with the guideway.
3. A filing device comprising a bottom, a back, a follower movable toward and away from the back, and a card guide, said card guide having a depending screw-threaded projection, the bottom having a slot disposed 20 transversely of the guide and receiving the threaded projection, and a nut on the underside of the projection whereby the guide may be adjusted laterally on the bottom.
4. A filing device comprising a bottom, a back rising therefrom, a follower movable toward and away from the back, and a card guide, said card guide consisting of a channel having its edges resting upon the bottom member, a rod secured within the channel and having depending screw-threaded 25 terminals, the bottom being provided with slots 30 extending transversely of the guide and receiving the screw-threaded terminals, and 35 nuts on the screw-threaded terminals and at the underside of the bottom, whereby the guide may be adjusted laterally. 45
5. A filing device comprising a bottom, a back rising therefrom, a follower movable toward and away from the back, and a card stop carried by the bottom at one side thereof and adjustable transversely of the 50 direction of movement of the follower.
6. A filing device comprising a bottom, a back rising therefrom, a follower movable toward and away from the back, and an adjustable card stop consisting of a rod 55 located at one side of the bottom and extending in the direction of movement of the follower, said rod having depending arms provided with lateral projections supported on the bottom, and clamping means engaging said projections to permit endwise adjustment thereof. 60
7. A filing device comprising a base, a bottom hinged at one end to the base and divided into a pair of sections having a hinge joint capable of breaking upwardly, a back rising from the rear bottom section, alined guideways on the bottom sections, a follower mounted to travel on the alined guideways, alined guides carried by the bottom sections at opposite sides of the guideways, a card stop carried by each of the bottom sections at one edge thereof, the base being provided at opposite sides with a series of transverse projections, the front bottom section having feet for selective engagement with the projections to prop the bottom in an adjusted position with its hinge joint broken upwardly. 70 75
